UNITED STATES PATENT OFFICE

SAMUEL A. NEIDICH, OF EDGEWATER PARK, NEW JERSEY, ASSIGNOR TO SYLVANIA INDUSTRIAL CORPORATION, OF FREDERICKSBURG, VIRGINIA, A CORPORATION OF VIRGINIA

VISCOSE TREATING APPARATUS

Application filed February 12, 1929. Serial No. 339,470.

The operations of forming viscose products from pulp ordinarily occupy two weeks time. Altho most of that time is required to effect the chemical changes incident to the several steps in the process; the conversion of viscose to cellulose hydrate ordinarily requires from six to seven hours time when such operations are effected by alternately charging and discharging the required liquids with respect to containers in which the viscose is treated. However, such conversion may be effected in less than two hours, if the time ordinarily wasted in the charging and discharging operations may be saved. Therefore, the purpose and effect of this invention is to provide means for effecting, at maximum speed, a substantially continuous process of conversion of viscose to cellulose hydrate. Such a process includes the successive subjection of the viscose filaments to the action of acid, alkali, and water. However, as hereinafter described, my improved apparatus includes a circular series of eighteen tanks or tubs, for containing liquids, and is so organized that further treatment of the filaments may be effected during a cycle of operation of the apparatus. For instance, the filaments may be washed, dyed, and washed again after their conversion. In that specific process, the apparatus includes means for subjecting the viscose to the action of (1) a strong aqueous solution of sulphuric acid, (2) an aqueous solution of sodium phosphate, (3) water, (4) a weak aqueous solution of sulphuric acid, (5) water, (6) dye liquor, (7) hot water, and (8) cold water.

My invention relates to apparatus of the type claimed in Letters Patent of the United States No. 1,616,918 granted to me February 8, 1927; wherein a rotary carriage is arranged to support a circular series of receptacles, each adapted to receive trays of viscose filaments, and liquids for treating them; said carriage being turned to successively subject such filaments to the action of the different liquids, which are successively supplied to and discharged from said receptacles by the automatic operation of series of valves.

The form of my invention herein disclosed differs from that of said Letters Patent, in

that bodies of the several liquids aforesaid are continuously maintained in respective stationary tubs, and the rotary carriage is arranged to support the filament trays independently of the liquid containers, and to not only intermittently turn to present the trays in registry with such stationary tubs, in succession, but to be lowered and raised to successively submerge the filaments in the liquids in said tubs and raise the filaments therefrom. As hereinafter described, the means for raising and lowering said carriage is adapted to repeatedly dip the filaments up and down in the liquids in the tubs, to cause the liquids to surge thru the filaments in the tubs. Moreover, means are provided to continuously circulate the several liquids aforesaid to, in, and from the respective tubs, during the operation of the apparatus, without the provision of automatically operative valves as aforesaid.

The several features of my present invention, differing from that disclosed in said Letters Patent, are advantageous in that the cost of construction of the apparatus is very much less and the operation thereof is facilitated.

My invention includes the various novel features of construction, arrangement, and method of procedure hereinafter more definitely specified.

In said drawings; Fig. I is a diagrammatic elevation of apparatus conveniently embodying my invention; showing the general arrangement of the means for maintaining the circulation of the several liquids with respect to the circular series of tubs into which the filaments are successively dipped as aforesaid.

Fig. II is a plan view of said rotary carriage, the circular series of tubs subjacent thereto, and their appurtenances.

Fig. III is a somewhat diagrammatic vertical sectional view of said series of tubs, carriage, and appurtenances thereof.

Fig. IV is an end elevation of one of the radially extending, pivoted, tray supporting frames indicated in Figs. II and III.

Fig. V is a transverse sectional view of one of the filament trays and its appurtenances.

Fig. VI is a plan view of the mechanism

for lifting, turning, and lowering said rotary tray carriage.

Fig. VII is a side elevation of said mechanism shown in Fig. VI.

Fig. VIII is a transverse sectional view of said mechanism, taken on the lines VIII, VIII in Figs. VI and VII, in the direction of the arrows on said lines.

Fig. IX is a diagram of the electric circuits of said apparatus.

As indicated in Fig. I; the elements of the apparatus are preferably distributed upon three levels, 1, 2, and 3, which may be respective floors in a suitable building inclosure.

Upon the first floor; I provide what I herein-after term a series of primary containers 5 which are the primary receptacles for the respective liquids required and in which such liquids may be prepared, if desired. Each of said primary containers 5 is provided with a discharge conduit 6, leading to respective pumps 7 and thence to a series of secondary containers 8, 9, 10, and 11, located on the third floor. Each of said secondary containers has a discharge conduit, respectively 13, 14, 15, and 16, controlled by respective valves 18, 19, 20, and 21, and leading to respective tubs 23, 24, 25, and 26. The level of the liquids in said tubs, thus supplied, is determined by the height of respective outlet pipes 28, 29, 30, and 31, which lead back to the respective primary containers 5. As above indicated, the secondary containers 8, 9, 10, and 11 may respectively contain a strong aqueous solution of sulphuric acid, a weak aqueous solution of sulphuric acid, an aqueous solution of sodium phosphate, and dye liquor. As indicated in Fig. I, the containers 10 may have steam heating coils 33 therein; so that the sodium phosphate solution may be heated to the boiling point, if desired. Moreover, hot water may be supplied from the main 34 and cold water from the main 35.

Referring to Fig. II; in the use of said apparatus in a process of converting and dyeing viscose filaments; the tub 23 is the initial tub in the series into which the filaments are successively dipped, and contains what is termed "strong" sulphuric acid solution, to wit, an aqueous solution containing, say, three percent, of such acid. As hereinafter described, such filaments are progressed from tub to tub, in the circular series of eighteen, clockwise. The second tub in such succession is marked 37 and is left empty to receive, from the filaments, the drippings of the strong sulphuric acid solution to which they have been subjected in the tub 23. Said tub 37 may have a discharge conduit 38 leading back to the respective primary container 5 containing such strong acid solution. The next four tubs in such succession in said series, and which are marked 24 in Fig. II, are supplied with the aqueous solution of sodium

phosphate, say, one and one-half percent, of that chemical. The next tub in such succession, and which is marked 40 in Fig. II, is supplied with water, conveniently from said cold water main 35. The level of the water in said tub is determined by the height of the overflow pipe 41 which leads to a waste outlet. The next two tubs in such succession, and which are marked 25 in Fig. II, are supplied with weak sulphuric acid solution, to wit, an aqueous solution containing one and one-half percent, of such acid. The next tub in such succession and which is marked 42 in Fig. II, is supplied with water, conveniently from said cold water main 35. The level of water in that tub is determined by the height of the overflow pipe 43 which leads to a waste outlet. The next six tubs in such succession and which are marked 26 in Fig. II, are supplied with dye liquor, which may be an aqueous solution containing 15/100 of one percent, of the dye. The next tub in such succession, and which is marked 45 in Fig. II, is supplied with hot water, conveniently from the main 34. The level of the water in that tub is determined by the height of the overflow pipe 46 which may lead to a waste outlet. The last in such succession of the eighteen tubs in said series, and which is marked 48 in Fig. II, is supplied with cold water, conveniently from said main 35. The level of the water in said tub is determined by the height of the overflow pipe 49, which may lead to a waste outlet.

I find it convenient to form said tubs of vitrified earthenware or other ceramic material.

The filaments to be treated as above contemplated are conveniently held in individual loosely coiled masses 51, in devices such as are best shown in Fig. V, including a cylindrical pot-shaped filament tray 52, formed of a band of bakelite, having an inner annular flange 53 at the bottom thereof formed of rubber, upon which rests a perforated disk 54 of porcelain 54, forming a foraminous bottom for such tray. In order to prevent the filament 51 from being displaced out of the tray, when the latter is lowered into the liquid; I find it convenient to provide each such tray with an upper screen closure 55, comprising an annular band of bakelite fitting somewhat loosely in the tray 52 and having, at the bottom thereof, a screen fabric 56 of one and one-half inch meshes, preferably formed of Monel metal wire. Two such trays 52 may be supported, during the treating operation, upon each pair of opposed angle rails 58, which are formed of porcelain or other ceramic. As indicated in Fig. IV; each pair of such rails 58 is suspended, by Monel metal hangers 59, which are rigidly pendent from a tray supporting frame 60. The stop bar 61, which is also pendent from said frame, serves to limit the radially in-

ward movement of said trays on said rails. Such frames 60 are conveniently made of cast aluminum and are independently hinged upon pintles 63 supported in brackets 64 fixed upon the rotary carriage 65 which is rigidly connected with the vertical shaft 66 by which said carriage and its appurtenances, including the trays of filament, are raised, lowered, and turned from tub to tub in the circular series, as hereinafter described. Each of said frames 60 includes a pair of downwardly extending flanges 68, each having, extending therethru, an axially adjustable set screw 69. Said set screws bear against the respective brackets 64 on the carriage and determine the precise elevation at which said tracks 58 are normally presented, during the turning movement of the carriage. Said frames 60 are thus pivoted so that they may yield upwardly, if, when the carriage is lowered, said tracks 58 encounter any obstruction preventing them from descending to the full extent intended. For instance, if the carriage is accidentally stopped and lowered with one of the rails 58 overhanging the side wall of the tub into which it is designed to lower it; lowering movement of the carriage will simply tilt the frame upwardly without breaking it or any of its appurtenances.

Referring to Figs. VI to VIII; said rotary carriage shaft 66 is mounted for rotation and vertical reciprocation in the bearing 71 on the second floor; which bearing is in the stationary housing 72 and has the lubricating oil pocket 73 above it and the felt packing 74 below it, to limit leakage of the oil down said shaft. Said shaft is also mounted for rotation and vertical reciprocation in the bearing bracket 75 on the base plate 76 which is stationary on a scaffolding 77 between the first and second floors. Said base plate 76 has the roller bearing 80 for said shaft and supports the worm gear 81 which is mounted to turn freely in the roller bearings 82 and 83 between said bracket 75 and base plate 76. Said gear 81 has a key 85 extending in the key way 86 in the portion of said shaft 66 which reciprocates thru said worm gear 81; whereby said shaft may be turned without interference with its vertical reciprocation.

Said rotary carriage shaft 66 has the collar 87 rigidly connected therewith and by which it is raised and lowered by means of the lever 88 which is fulcrumed at 89 on the bracket 90 rigidly connected with said base plate 76. Said lever 88 includes the fork 91 carrying opposite rollers 92 upon which said shaft collar 87 continually rests. The weight of said shaft 66 and its appurtenances, including said carriage 65 etc., is almost completely counterbalanced by the weights 94 which are carried by the link 95 at the end of said lever 88 opposite to said shaft 66, the weight of said shaft and its appurtenances, not thus counterbalanced,

is borne by the rotary cam 96 which is ridden by the rollers 97 on said lever 88. Said cam 96 is of such configuration that every desired vertical movement of said shaft 66 and the filament carriage supported by it, is effected in proper sequence with the intermittent rotary movement of said shaft. The relative rotary movements of said shaft 66 and cam 96 are conveniently effected by the driving shaft 99 which may be constantly rotated by connection with a suitable motor 98 and which has, rigidly connected therewith, the crown clutch member 100. Intermittent rotary movement of said shaft 66 and cam 96 is obtained from the continuous rotary movement of said shaft 99, by means of the crown clutch member 101, which is mounted to slide axially upon the shaft 102 which is journaled, in axial alignment with said shaft 99, in the bearings 104 and 105 on said base plate 76. Axial movement of said clutch member 101 to engage and disengage said clutch member 100, is effected by the lever 107 which is fulcrumed at 108 on said base plate 76, has a stud 109 engaging the groove 110 in said clutch member 101, and is connected by the link 111 with the lever 112 which is fulcrumed at 113 on the second floor 2, so as to be readily accessible to the operator of said carriage 65 and its appurtenances. Said shaft 102 carries the worm 115 continually engaged with said worm gear 81, whereby said carriage shaft may be intermittently turned; when said worm is operatively connected with its shaft 102 by its friction clutch 116, as hereinafter described.

Said shaft 102 also carries, rigidly connected therewith, the worm 117, continually engaged with the worm gear 118 on the cam shaft 120 with which said cam 96 is rigidly connected. The construction and arrangement of the driving mechanism aforesaid are such that said cam shaft 120 is continually turned, clockwise as indicated in Fig. VII, and the carriage 65 is turned clockwise as indicated in Fig. II; whenever the clutch member 101 is engaged with the driving clutch member 100 on the shaft 99.

Said cam shaft 120 carries the cam 121 having the roller 122 in cooperative relation with the clutch lever 123 which is mounted on the rock shaft 124 journaled in the bearings 125 and 126 which are stationary on said base plate 76. Said clutch lever 123 has the roller 128 engaged in the groove 129 on the clutch member 130 which is thereby axially movable on said shaft 102. Clockwise movement of said cam shaft 120, as indicated in Fig. VII, causes the roller 122 on said cam 121 to intermittently encounter said clutch lever 123, push it down out of the path of said roller 122, and thus move said clutch member 130 to the right in Fig. VII; thus engaging said clutch member 116 to friction-

ally engage said worm 115 with said shaft 102 to effect the intermittent turning movement of said carriage shaft 66, at the proper time in the cycle of operation of said carriage 65. Said clutch lever 123 also has the roller 132 which rides upon the disk flange 133 of said clutch member 116 and is adapted to drop into the notch 134 of said disk when said clutch member 130 is in the disengaged position shown in Fig. VII. The construction and arrangement of the various elements aforesaid by which said flange 133 is turned, are such that when its notch 134 is thus engaged by the clutch lever roller 132; the porcelain tracks 58, carrying the filament trays 52, are in registry with the respective tubs 23 etc., in which said filaments are to be dipped.

However, as a safety device, to prevent accidental lowering of the carriage 65 and its appurtenances when said tracks 58 are not in proper registry with said tubs 23 etc., I provide the slide bolt 136 which is mounted to reciprocate horizontally in the bearings 137 and is operatively connected with the arm 138 of said clutch lever 123, by the bell crank lever 139 and link 140; so that, when said roller 132 is uplifted from the notch 134 of the clutch flange 133, said bolt 136 is thrust 30 away from the observer in Fig. VII and beneath said lever 88 so as to uphold the latter and the unbalanced portion of the weight of the carriage 65 and its appurtenances until said roller 132 falls into said notch 134, when 35 the latter is again presented in registry therewith. Said slide bolt 136 thus prevents lowering movement of said carriage 65 and its appurtenances except when the porcelain tracks 58 are properly registered with their 40 respective tubs 23 etc.

Moreover, I prefer to provide said apparatus with means to automatically stop the operation of the machine by the shaft 102; if and when said roller 132 fails to drop into 45 the notch 134 of the clutch flange 133 at the proper time. Such means includes the arm 142 on the clutch lever 107 and the weight 143 which, when released, drops upon said arm 142 and shifts the clutch member 101 to 50 the left in Fig. VII, by said lever 107. Said weight 143 is conveniently upheld by the solenoid coil 144 which is energized by the circuit including the conductors 145 and 146. Said circuit includes the two push switches 55 148 and 149 which are spring pressed so as to be normally closed, in parallel relation with each other, but in series with said coil 144. As long as either of said switches remains closed, the circuit energizing said coil 60 144 is closed and the weight 143 upheld. Either of said switches may be pushed to open the circuit thereat, without dropping the weight, but if both switches are contemporaneously operated to open the circuit, said 65 weight drops and the machine stops. Said

switch 148 is arranged to be operated by the lever 151 which is rigidly connected with the rock shaft 124, so that the circuit is opened at said switch 148 whenever said roller 132 is uplifted from the notch 134 to roll upon the clutch flange 133 as the latter turns. The switch 149 is arranged to be operated by the roller 152 on the arm 153 which is rigidly connected with the cam shaft 120. Said arm 153 is so positioned on said shaft that said roller 152 pushes upon the switch 149 immediately after said notch 134 has been presented in registry with said roller 132; so that, if the switch 148 has not been permitted to close by the fall of said roller 132 into said notch, and consequent withdrawal of the arm 151 from said switch 148; the circuit remains open at that switch and is, thereupon, immediately opened at the other switch 149, so that the circuit energizing said coil 85 144 is broken and the weight released to stop the apparatus as aforesaid.

As the action of the worms on said shaft 102 tends to thrust the latter axially to the left in Fig. VII; the bearing 105 includes anti-friction balls or other rollers to sustain such stress and minimize the friction incident thereto. Moreover, I find it convenient to lubricate the lower end of the shaft 66 and the worm gear 81 and worm 115 connected therewith, by mounting upon the under side of said base plate 76, the oil well 156 into which the lower end of said shaft 66 dips and forces oil upwardly, to said parts, each time said shaft is lowered.

However, I do not desire to limit myself to the specific construction and arrangement herein set forth, as it is obvious that various modifications may be made therein without departing from the essential features of my invention, as defined in the appended claims.

I claim:

1. In viscose treating apparatus, the combination with a rotary carriage, having means arranged to support a circular series of trays, for rotation in coaxial relation with said series; of a circular series of stationary tubs disposed beneath said series of trays; means arranged to intermittently raise and lower said carriage; and means arranged to intermittently turn said carriage; whereby, said trays may be automatically dipped into and removed from said tubs, in succession; wherein the tray supporting means are radially extending frames respectively, independently, hingedly connected to the carriage, and free to be upturned by any subjacent obstruction encountered thereby, when the carriage is lowered; whereby, breakage of said frames, by such obstructions, is prevented.

2. In viscose treating apparatus, the combination with a rotary carriage, having means arranged to support a circular series of trays, for rotation in coaxial relation with said series; of a circular series of stationary tubs

disposed beneath said series of trays; means arranged to intermittently raise and lower said carriage; and means arranged to intermittently turn said carriage; whereby, said trays may be automatically dipped into and removed from said tubs, in succession; wherein the tray supporting means include pairs of parallel rails, extending radially from said carriage, and arranged to slidably engage the trays between them.

3. In viscose treating apparatus, the combination with a rotary carriage, having means arranged to support a circular series of trays, for rotation in coaxial relation with said series; of a circular series of stationary tubs disposed beneath said series of trays; means arranged to intermittently raise and lower said carriage; and means arranged to intermittently turn said carriage; whereby, said trays may be automatically dipped into and removed from said tubs, in succession; wherein the tray supporting means include pairs of parallel rails, extending radially from said carriage, and arranged to slidably engage the trays between them; and means hingedly connecting each pair of rails with said carriage, independently; whereby said pairs of rails may be independently upturned.

30 4. In viscose treating apparatus, the combination with a rotary carriage, having means arranged to support a circular series of trays, for rotation in coaxial relation with said series; of a circular series of stationary tubs disposed beneath said series of trays; means arranged to intermittently raise and lower said carriage; and means arranged to intermittently turn said carriage; whereby, said trays may be automatically dipped into and removed from said tubs, in succession; wherein the tray supporting means include pairs of parallel rails, extending radially from said carriage, and arranged to slidably engage the trays between them; means hingedly connecting each pair of rails with said carriage, independently; whereby said pairs of rails may be independently upturned; and respective adjustable means, independently limiting the downward turning movement of each pair of rails.

5. In viscose treating apparatus, the combination with a rotary carriage, having means arranged to support a circular series of trays, for rotation in coaxial relation with said series; of a circular series of stationary tubs disposed beneath said series of trays; means arranged to intermittently raise and lower said carriage; and means arranged to intermittently turn said carriage; whereby, said trays may be automatically dipped into and removed from said tubs, in succession; comprising a safety device arranged to stop the movement of the carriage if and when the latter is improperly placed for such movement with respect to the tubs; including an

electric motor arranged to normally effect the movements of the apparatus in proper sequence; an energizing circuit for said motor; two electric switches, in said circuit, in parallel relation with each other and in series 70 relation with said motor; means automatically movable with the normal movement of the apparatus adapted to successively open said switches, independently of each other, and permit their alternate closure under normal conditions; whereby both switches are opened under abnormal conditions to break said circuit and stop said motor.

In testimony whereof, I have hereunto signed my name at Philadelphia, Pennsylvania, this third day of December, 1928.

SAMUEL A. NEIDICH.
